UNITED STATES PATENT OFFICE.

CARL A. G. PFANNE, OF HOBOKEN, NEW JERSEY.

DEVICE FOR GRAINING LITHOGRAPHIC STONES.

990,384.

Specification of Letters Patent. Patented Apr. 25, 1911.

Application filed June 30, 1910. Serial No. 569,646.

To all whom it may concern:

Be it known that I, CARL A. G. PFANNE, a citizen of the United States of America, and a resident of Hoboken, county of Hudson, 5 State of New Jersey, have invented certain new and useful Improvements in Devices for Graining Lithographic Stones, of which the following is a specification.

This invention has reference to improvements in devices for graining lithographic stones by means of which the graining surface required by the artist is produced as well as if the stone were grained by the most skilled handwork. In addition thereto 10 the stones are grained in a fraction of the time required for hand graining and naturally more uniform results are obtained.

The invention is illustrated in the accompanying drawings in which: 20 Figure 1 represents in perspective view a device for graining lithographic stones embodying in desirable form the present improvements. Fig. 2 shows same in front elevation. Fig. 3 is a plan view of the device 25 shown in Figs. 1 and 2 partly broken away. Fig. 4 is a like view in side elevation. Fig. 5 is a sectional view on line 5—5 of Fig. 4. Fig. 6 is a top plan view of the device shown in Figs. 1 and 2 with parts broken away and 30 Fig. 7 illustrates in sectional view a detail.

Similar characters of reference denote like parts in all the figures.

In the drawings A designates a pulley or wheel, shown as affixed to a shaft, as B. 35 The wheel A may be turned by any desired means of power. The shaft B is shown as working in a sleeve, C¹, cast on or secured to a plate, as C. This plate C may be made integral with or secured in any desired manner to the frame D.

The shaft B is shown as provided with a gear wheel b which meshes with another gear wheel as e on a shaft, as E. This shaft E is shown as mounted between the plate C 45 and another plate F. The last mentioned plate may also be made integral with or secured in any desired manner to the frame D.

As shown, the shaft E is provided with a cam, as G, having a groove g therein. Into 50 this groove g rollers, as h are shown as fitted. These rollers h are shown as attached to rods H, and the rods H are shown as fastened to pieces, as I. These pieces I are shown as passing through bearings, as F¹, on extensions of the plate F.

To the pieces I cross sleeves, as I¹, are

shown as secured, and in these cross sleeves I¹ rods as J are shown as inserted. Two of the cross sleeves I¹ are shown as provided with screws i and the other two of the cross sleeves 60 are shown as not provided with screws i. The screws are intended to fasten the cross sleeves I¹ which are so provided with such screws to the rods J which are inserted in them. Failure to provide any means for 65 fastening the other two cross sleeves to the rods J inserted in them leave these rods J, not so fastened, free to ride in their cross sleeves I¹.

To the rods J links, as J¹, are shown as attached. These links J¹ are shown as also attached to center links, as J², and projections j² are shown as provided on the upper sides of these center links J². The projections j² are intended to fit in suitable openings k 70 provided in the lower ends of brackets, as K. The brackets K are shown as held together by a right and left hand screw as K¹, and this screw K¹ is shown as provided at one end with a head so that it may be easily 75 turned to adjust the brackets K relatively to each other.

K² designates a loose fitting sleeve surrounding a portion of the screw K¹. This sleeve K² may be held in position on the 85 screw K¹ by means of a screw as k¹.

L designates a rope shown as fastened at one end to the sleeve K². This rope is shown as passing over grooved rollers m and as having adjustable weights as L¹ attached to 90 the other end thereof. The rollers m are shown as mounted in a cross bar, M, supported upon a shaft, as M¹, and this shaft M¹ is shown as extending through an opening in the plate F and as resting in a ball bearing fixture M² in the base of the machine, as 95 shown in detail in Fig. 7.

N designates brackets shown as held together by a right and left hand screw as N¹, which screw is shown as provided at about 100 its center with a head n to enable the screw to be readily turned. The brackets N are also shown as having pins as n¹ by which the stone may be securely bolted in the brackets N. The brackets K and N are shown as 105 fastened together by bolts, n², and these bolts n² act as hinges on which the stone may be turned.

The shaft E is shown as provided with a gear wheel e¹ which meshes with other gear 110 wheels o on the shafts O. These shafts O are shown as mounted between the plates C

and F and as having projections o^1 on their upper ends. These projections o^1 are intended to fit into openings p in the under side of a plate, as P. The projections o^1 are so arranged that as they travel around in the openings p the plate P will receive an eccentric motion. The plate P is shown as provided with a rim p^1 and as having a grooved space p^2 inside the rim p^1 . A plate 10 P¹ of hardened material, such, for instance, as glass or steel, may cover the surface of the plate P inside the grooved space p^2 . The plate P is shown as resting on a frame Q provided with ballbearings as q. Guide 15 pins, as f, may be provided to retain the frame Q in position.

I will now describe the mode of operation of the machine.

A lithographic stone as R is placed on the 20 surface of the plate P inside the grooved portion p^2 thereof. The brackets N are securely fastened to the sides of the stone R by the adjustment of the screw N¹, and the brackets K are adjusted to proper position 25 by turning the screw K¹. The brackets N and K are then fastened together by the bolts n². The surface of the stone R which is to be grained, will of course, rest on the surface of the plate P. The surface of the 30 plate P having had placed thereon a sufficient quantity of graining material, such for instance as sand and water, the wheel or pulley A is caused to revolve, thereby causing the revolution of the shaft B, and from 35 the shaft B motion is transmitted to the shaft E by means of the gearings which mesh with each other. The revolution of the shaft E also causes the revolution of the shafts O, through the instrumentality 40 of the gearings e¹ and o. The revolution of the shaft E gives motion to the cam G, and the rollers h which work in the grooves g of the cam G in turn cause the movement of the rods H. These rods H in turn move 45 the pieces I and with them the cross sleeves I¹. The two cross sleeves I¹ to which the corresponding bars J are fastened by the screws i move such bars J and these bars transmit movement to the links J¹, and 50 through the links J¹ to the center links J². The projections j² on the center links J² projecting into suitable openings in the brackets K move the brackets K and these brackets K in turn move the brackets N 55 which are secured to the stone R. The motion of the cam G thereby gives the stone R a reciprocating movement. The pieces I which are not fastened in their corresponding sleeves I¹ meanwhile play in their sleeves. While this reciprocating movement is being given to the stone R the shafts O are carrying around their projections o¹, thereby giving an eccentric movement to the 60 plate P on the surface of which the stone R rests. In this way the grains of sand to

which the surface of stone R is exposed are caused to so move that any design which may have been upon this surface of the stone R when it was placed on the plate P will be speedily removed. The counter-balancing weights L enable the weight with which the stone R is held against the plate P to be so adjusted as to meet the requirements of the operator. When the operator desires to raise the stone to see how the 70 work is progressing he may, with slight effort and, if desired, by adding weights to the pile L¹ raise the stone R up from the plate P, and when the stone R has been raised to a sufficient height he may then 75 turn it around on the bolts n² to expose the surface of the stone R to examination. It will of course be understood that the brackets K will be so shaped that they will not interfere with the turning of the stone 80 R on the bolts n². If on examination the operator finds that the design on the stone R has not been satisfactorily removed he simply lowers the stone back onto the surface of the plate P and permits the machine 85 to complete the effacement of the design. When the design has been satisfactorily removed the graining material to which the stone has been exposed may be removed and in place thereof other graining material 90 may be placed on the plate P and the operation of the machine continued until the surface of the stone has been given that grained surface which is required by the artist. When the work of graining the 95 stone is completed the stone may be raised and turned around by means of the cross bar M and lowered to a carriage. When the stone has been loosened from the brackets in which it was held the machine is 100 ready for the next stone.

I claim as my invention:

1. A device for graining lithographic stones, comprising a plate on the top surface of which the lithographic stone is 110 placed, means for imparting an eccentric motion to said plate, stone clamping and supporting devices, means for imparting reciprocating motion to said devices, and a device for counter-balancing partly the 115 weight of the stone during graining.

2. In a device for graining lithographic stones, a ballbearing supported plate having recesses in its bottom surface portion and a smooth top surface on which the stone is 120 placed, rotatable shafts below having projections which extend into the recesses of the plate so arranged that eccentric motion is imparted to the plate, means for clamping and supporting the stone, and means for imparting reciprocating motion to the stone 125 clamping devices.

3. In a device for graining lithographic stones, a plate having recesses in its bottom surface portion and a smooth top surface on 130

which the stone is placed, a ballbearing device upon which the plate rests, means for holding said device in position, and rotatable shafts below having projections which extend into the recesses of the plate so arranged that eccentric motion is imparted thereto.

4. In a device for graining lithographic stones, a shaft, a cam operated by said shaft, rods moved by said cam, pieces to which said rods are fastened, sleeves secured to said pieces, bars passing through said sleeves, links attached to said bars, and means for transmitting the motion of said links to the stone, substantially as specified.

5. In a device for graining lithographic stones, a ballbearing supported plate having recesses in its bottom surface portion, rotatable shafts below having projections which extend into the recesses of the plate to impart eccentric motion thereto, means for clamping and supporting the stone, and a cam operated device for imparting reciprocating motion to the stone clamping device and stone.

6. In a device for graining lithographic stones, a ballbearing supported plate having recesses in its bottom surface portion, rotatable shafts below having projections which extend into the recesses of the plate to impart eccentric motion thereto, means for clamping and supporting the stone, a shaft with cam, rods moved thereby, pieces connected to said rods, sleeves on said pieces, bars passing through the sleeves, links attached to the bars, and means for transmitting the motion of said links to the stone.

7. In a device for graining lithographic stones, adjustable brackets, brackets in connection with the first, links, means for detachably connecting the links and brackets, links connected to said first mentioned links, bars attached to the links, heads into which the bars are inserted, pieces secured to said heads, rods attached to said pieces, a cam, means whereby said rods are attached to said cam, and means for moving said cam.

8. In a device for graining lithographic stones, the combination of a shaft, a cam on said shaft, rods operated by said cam, pieces to which said rods are fastened, sleeves secured to said pieces, bars passing through said sleeves, links connected to said bars, other links connected to the first mentioned

links, projections on said links secondly mentioned, brackets extending within reach of said projections, openings in said brackets into which said projections may fit, means for adjusting said brackets and a counter-weight attached to said brackets.

9. In a device for graining lithographic stones, the combination of a shaft, a cam operated by said shaft, rods operated by said cam, pieces to which said rods are fastened, sleeves secured to said pieces, bars held in said sleeves, links connected to said bars, other links connected to said first mentioned links, projections on said secondly mentioned links, brackets within reach of said projections having openings in said brackets into which said projections may fit, means for adjusting said brackets, a counter-weight attached to said brackets, other brackets, means for adjusting said last mentioned brackets and means for connecting said last mentioned brackets with the first mentioned brackets.

10. In a device for graining lithographic stones, the combination of a shaft, a cam operated by said shaft, rods operated by said cam, pieces adjusted to said rods, heads secured to said pieces, bars held in said pieces, links attached to said bars, other links attached to said first mentioned links, projections on said secondly mentioned links, brackets within reach of said projections, openings in said brackets into which said projections may fit, means for adjusting said brackets, other brackets attached to the first mentioned brackets, means for adjusting said secondly mentioned brackets, a counter-weight attached to said first mentioned brackets, shafts having projections thereon, a plate having openings on its under side into which said last mentioned projections may fit, said projections being so arranged that when the shafts last mentioned are revolved said plate will be given an eccentric motion, a movable frame on which said plate rests, and means for holding said plate in position.

Signed at Jersey City, N. J., this 28th day of June, 1910.

CARL A. G. PFANNE.
